UNITED STATES PATENT OFFICE.

HENRY L. ZABRISKIE, OF WESTFIELD, NEW JERSEY, ASSIGNOR TO DIEHL MANUFACTURING COMPANY, A CORPORATION OF NEW JERSEY.

ELECTRIC MOTOR.

1,084,590.

Specification of Letters Patent. Patented Jan. 13, 1914.

Application filed July 15, 1911. Serial No. 638,613.

To all whom it may concern:

Be it known that I, HENRY L. ZABRISKIE, a citizen of the United States, residing at Westfield, in the county of Union and State 5 of New Jersey, have invented certain new and useful Improvements in Electric Motors, of which the following is a specification, reference being had therein to the accompanying drawings.

- 10 This invention relates to an improvement in controlling devices for small motors designed for service where frequent starting and stopping is required, and its object is to combine such controlling mechanism with a 15 motor-body so that the structure will be compact and self-contained and all its moving parts, excepting the pulley upon the motor-shaft, shall be protected from injury in transportation and subsequent operation. 20 One of the chief advantages of such a structure is that all of its parts may be assembled and adjusted independently of the machine which it is required to drive, so that its installation may be readily effected by any one 25 unskilled in the construction and adjustment of dynamo electric machines.
- In the preferred form, the improvement is embodied in an electric motor of the series alternating-current commutator type and 30 comprising a casing provided with a plurality of pole-pieces each surrounded by a field-magnet coil and between which is disposed the rotary armature whose shaft carries externally to said casing the pulley 35 through which power is transmitted to the belt connected with the machine to be driven. The field-magnet coils are each divided into main and auxiliary sections. The controller comprises a plurality of independent series 40 of circularly arranged fixed contact-studs, the corresponding studs of each series being adapted for connection by an oscillatory controller-arm provided with connected brushes resting upon said contacts. The auxiliary 45 sections of the field-coils are connected by conductor wires or taps in such relation that the corresponding sections are simultaneously thrown into and out of the field circuit by the action of the controller-arm.
- 50 The contact-points of the controller are arranged in the motor-casing and within the magnetic influence of the pole-pieces which serve to prevent any arcing produced by the action of the controller-arm in successively 55 making and breaking contact between the

opposite contact-points, and the controller-arm is mounted upon the inner face of the end cover of the motor-casing upon whose outer face is fulcrumed a brake-lever carrying at one end a brake-shoe in operative relation with the rim of the driving pulley and at the other end a stud normally pressed in contact with a plural-stepped segmental cam carried by the controller-arm which latter is attached to a chain or other suitable connection with means external to the motor-casing for actuating the controller, and through it controlling the spring-pressed brake-lever.

The invention will be more fully understood by reference to the accompanying drawings, in which—

Figure 1 is a partial sectional side elevation of an electric motor provided with the present improvements; and Fig. 2 an end view of the same with the pulley rim in section. Fig. 3 is an end view of the motor-casing with the end cover and the brake-lever removed. Fig. 4 is a perspective view representing the controller and the brake-lever detached from the motor-frame, and Fig. 5 a similar view showing portions of the controller-arm and the end cap. Fig. 6 is a diagram to show the principle of operation of the controller.

The motor is shown constructed with a 35 casing comprising the main body 1, rearward end cover 2 and forward end cover 3, the end covers being provided with bearing bosses in which is journaled the motor-shaft 4 carrying the armature 5 rotating between 40 the inwardly extending pole-pieces 6 formed upon the laminated ring 7 secured within the casing, said pole-pieces being embraced by the sectional field-magnet coils 8. The motor-casing is shown provided externally 45 with the boss 9 to which is secured by means of the screws 10 a foot-piece 11 by which it is attached to a suitable support in operative 50 relation with the machine to be driven.

The body 1 of the casing is provided internally near the forward end with lugs 12 to which is secured by means of the screws 13 the annular plate 14 of fiber or other suitable insulating material in which are secured the series of relatively insulated contact-studs 15 16 arranged in diametrically opposite series, each diametrically opposite pair of such contact-studs being connected to one extremity of corresponding sections of the field-magnet coils 8 by means of the conduc- 110

tor wires or taps 17 18, 17^a 18^a, 17^b 18^b, and 17^c 18^c, respectively, as represented diagrammatically in Fig. 6.

The inner face of the end cover 3 is provided with an inwardly extending tubular bearing boss 19 upon which is mounted the hub 20 of the controller-arm 21 which is formed at each of the opposite extremities with an aperture 21* containing the insulating bushing 22 embracing the tubular metallic brush-socket 23 whose other end portion is formed with a slot 24 and has secured thereon a clip 25 whose spaced ears 26 carry the cross-pin 27 supporting the coil-spring 28 having one arm 29 resting upon the inturned lip 30 of the adjacent ear 26 and another arm 31 extended laterally through the slot 24 and resting upon the outer end of the cylindrical carbon brush 32 disposed within the socket 23 and with its forward end resting upon one of the contact-studs 15 or 16 whose inner ends are provided with the clamp-nuts 33 for securing the extremity of the tap leading from its respective section of the field-coils to the contact-stud. The brush-sockets 23 are permanently connected together by means of the insulated wire 34.

The reduced inner portion 19* of the end cover bearing boss 19 has secured thereto by means of the screw 35 one extremity of the spiral spring 36 whose opposite end is formed with an eye embracing a stud-screw 37 projecting from the adjacent face of a lateral extension 38 of the controller-arm 21 which is also provided with a pin 39 projecting from its outer face and upon which is secured by means of the cross-pin 40 one end-link of the operating chain 41 passing through the lateral aperture 42 of the casing.

The spring 36 serves to normally maintain one end portion of the controller-arm in engagement with a stop-lug 43 upon the inner face of the end cover 3 with its brushes 32 connecting the dead contact points 15* and 16*. The drawing down of the chain by a treadle or other means serves to progressively connect the diametrically opposite contact-points so as to first throw into the armature circuit the entire motor-field and then reduce the active portion of the same section by section, until the opposite end portion of the controller-arm engages the stop-lug 44 upon the inner face of the end cap 3, when the taps 17^c and 18^c are connected to maintain in the circuit only the main field-coils. By progressively reducing the number of turns of the field-coils in the circuit, the speed is varied from a minimum, utilizing all of the field-coils, to a maximum, wherein all of the auxiliary sections are cut out. By disposing the contact-points within the magnetic influence of the field, the sparking and burning which

has been common to this class of controller heretofore is greatly reduced.

The controller-arm 21 is shown provided upon the side opposite the extension 38 with a segmental cam 45 formed in its operative edge with a series of indentations or recesses 46 corresponding in number with the live contact-studs of each series, and formed at one end with a deeper recess 47 which corresponds in position with the dead contact-studs 15* and 16*. Normally pressed in contact with this cam is the anti-friction roller 48 carried by the stud 49 projecting through an aperture 50 in the end cover 3 and secured upon the upper arm 51 of the angular brake-lever fulcrumed upon the outer face of the cover 3 by means of the stud-screw 52 and having secured to its depending arm 53 by means of the clamp-plate 54 and screws or rivets 55, the brake-block 56 formed of leather or other suitable yielding material. Secured upon the outer end of the motor-shaft 4 by means of the set-screw 57 is the hub 58 of the pulley 59 in the form of a hollow drum embracing the brake-lever and the inner face of whose rim is presented to the operative edge of the brake-block or shoe 56. The pulley hub 58 is provided with the V-shaped groove 60 to receive the belt by which the motor is connected with the machine to be driven.

The inner edge of the brake-lever arm 51 is formed with an aperture entered by one of the hooked ends of the brake-spring 61 whose other extremity enters a transverse aperture in the adjusting screw 62 tapped into the lug 63 upon the outer face of the cover 3 in which it is locked against turning by means of the lock-nut 64. By suitable adjustment of the screw 62, the tension of the spring 61 and the effectiveness of the brake may be determined.

The form of the pulley-wheel represented in the drawings, and comprising a rim extending inwardly from the hub, enables it to act as a housing to conceal and protect the brake mechanism for which it affords a shield. As will be readily seen, the pulley-wheel cooperates with the cover-plate 3, with its openings to receive the stud 49 and other parts, to effectively close the forward end of the casing so as to exclude dust and dirt from the operative parts.

It is evident that the openings in the front end cap represented in the drawings will perform the function of a portion of the ventilating apertures provided in practice, which latter do not materially reduce the effectiveness of the substantially closed casing in shielding the contained parts from disarrangement and otherwise protecting them in the manner described.

The cam-recess 47 affords sufficient clearance, when the circuit is open and the motor is at rest, to entirely release the roller-

stud 48 and thus permit the brake-shoe 56 to act upon the pulley-rim 59 under the full power of the spring; but as soon as the chain 41 is drawn downward in starting the motor, the roller-stud 48 rides up the inclined side of the pocket or recess 47 and shifts the brake-lever in opposition to its spring and maintains the same retracted throughout the period of operation of the motor.

10 While the peripheral notches 46 of the cam 45 are not sufficiently deep to wholly release the brake-lever and permit the same to resume operative relation with the pulley, they serve to yieldingly resist the movement 15 of the controller-arm from each pair of contact-studs to the next so as to insure the correct register of the brushes of the controller-arm with the corresponding contacts for a given speed of the motor. The 20 brake-lever therefore has a function in addition to that of arresting the movement of the motor, of insuring the proper register of the movable and fixed members of the controller to insure a perfect electrical connection 25 of the parts of the motor controlled thereby.

Referring more particularly to Fig. 6, it will be observed that the current from the line wire 65 enters and emerges from the 30 armature through the brushes 66 and commutator 67 and passes thence through the connection 68 into one of the field-coils 8 and thence through the other field-coil to the other line wire 69. The controller-arm 35 21 is represented diagrammatically as movable bodily intermediate the contact-studs which it is designed to connect, being shown in position to establish connection between the dead contact-studs 15^a and 16^a. Upon 40 the actuation of the controller-arm, which may be called the connector, connection is established, through the respective contact-studs, between the taps 17 and 18, thereby closing the circuit through the armature 45 and each entire field-coil. As the connector progresses from station to station, it successively connects the taps 17^a and 18^a, 17^b and 18^b and 17^c and 18^c, thereby cutting out the auxiliary sections whose terminals were 50 previously connected and reducing the number of turns in the field and increasing the speed of the motor up to the maximum, the brake having been maintained retracted from operative relation with the pulley 59 throughout the period of acceleration of the 55 motor-speed and during the operation of the motor at its highest speed as well.

According to the present improvement in its preferred form, both field-coils are subdivided correspondingly and means are provided for progressively cutting out equal sections from each so as to balance the field to insure uniformity of action of the motor at all speeds. It is evident, however, that 65 the controller may be readily connected with

a series of resistance coils adapted to be thrown thereby into and out of the motor circuit for varying the speed of operation of the motor.

From the foregoing description it will be observed that each of the movable members employed in controlling the action of the motor-shaft is mounted upon the removable end cover of the motor casing, so that the removal of the latter and the pulley 70 fixed upon the motor-shaft adjacent thereto is all that is necessary to effect the removal of such movable controlling parts for inspection and repair without removal of the armature or disturbing any of the electrical connections, the several contact-studs of the controller being sustained by the insulating ring 14 which is secured within the body of the motor casing, so that they may be permanently connected with their respective field-coil sections.

By reference more particularly to Fig. 2, it will be observed that the fulcrum-stud 52 for the brake-lever is disposed intermediate the motor-shaft 4 and the peripheral flange 90 59 of the pulley, and that the arm 53 of the brake-lever is extended in a direction opposite to that of rotation of the pulley as represented by the arrow in said figure. By this means, the brake-shoe is given a path 95 of movement around the fulcrum-stud 52 at an acute angle to the adjacent portion of the pulley-flange whereby a wedge-like or jamming action is produced between the brake and the pulley-flange which produces an effective arresting action with a comparatively light spring 61 for forcing the brake-shoe into operative relation with the pulley-flange. Thus the rotation of the pulley 100 materially assists the spring in pressing the 105 brake-shoe upon the pulley-flange, which would not be the case if the brake-lever were extended in the opposite direction from its sustaining fulcrum-stud.

The present improvement is shown in connection with a bipolar-machine, but it is evidently equally applicable to motors having any number of poles arranged in pairs, so long as each is provided with field-coils divided into the same number of sections 115 and each of such sections is connected to the corresponding contact of series corresponding in number with the pairs of pole-pieces. It is also evident that the present improvement is not limited to the specific details of 120 construction and arrangement of parts shown and described herein, but is susceptible of considerable modification in such particulars within the scope of the invention.

Having thus set forth the nature of the 125 invention, what I claim herein is:—

1. In an electric motor comprising a closed casing and an armature inclosed therein and rotating in a magnetic field, a controller disposed within and protected by the motor 130

- casing and provided with a series of fixed contacts disposed within the influence of said field, a movable contact member for establishing electrical connection between said contacts, a brake device for arresting the rotation of said armature, and an operative connection between said brake device and said movable contact member.
2. In an electric motor comprising a casing and an armature rotating in a magnetic field within the same, a controller disposed within the motor casing, a pulley disposed exterior to said casing and driven by the motor, a brake mounted upon the exterior of the motor-casing and in operative relation with said pulley and operatively connected with the controller, and means for operating the controller from the exterior of the motor casing.
3. In an electric motor comprising a plurality of magnetic pole-pieces and a rotary armature intermediate the same, a motor-shaft carrying said armature, a controller disposed within the motor casing and comprising a plurality of contacts arranged concentrically with the motor-shaft and in close proximity to and within the magnetic influence of said pole-pieces, and a controller arm also arranged within the motor casing and adapted to connect said contacts, means exterior to said casing for operating said controller-arm, a pulley upon the motor-shaft, a brake exterior to said motor casing and adapted for engagement with said pulley, and an operative connection between the controller-arm and said brake.
4. In an electric motor comprising a plurality of pole-pieces each carrying a sectional field-coil, and a rotary armature intermediate said pole-pieces, a controller comprising a plurality of fixed contacts arranged in series corresponding in number with the pole-pieces of the motor and in concentric relation with the armature and a movable contact member adapted for establishing connection between corresponding contacts of each series, and a series of taps each connecting one of the field-coil sections with a contact of its respective series whereby the controller may be operated to cut out simultaneously from each motor field-coil a corresponding section.
5. In an electric motor comprising a closed casing containing two pole-pieces each carrying a sectional field-coil subdivided into sections corresponding with those of the other field-coil, and a rotary armature intermediate said pole-pieces, a controller inclosed within said casing and comprising two circularly arranged series of fixed live contacts, those composing each series corresponding in number with the sections of each field-coil, and a controller-arm adapted to successively connect in pairs the contacts of one series with those of the other for establishing connections between the corresponding sections of said field-coils.
6. An electric motor comprising a casing constructed with a body portion carrying a plurality of magnetic pole-pieces and a removable end cover for said casing, a motor-shaft, an armature mounted upon said shaft intermediate the pole-pieces, a controller disposed within the motor casing and comprising fixed and movable members, a brake mounted upon the outer face of the end cover, a pulley secured upon said shaft adjacent the end cover and in operative relation with and embracing said brake, an operative connection between the movable member of the controller and said brake, and actuating means for the controller and brake.
7. The combination with an electric motor-frame comprising a body portion and a removable end cover therefor, of a controller having a series of stationary contacts secured within said body portion and a movable contact-connecting member mounted upon and sustained by the inner face of said cover, and controller actuating means.
8. The combination with an electric motor-frame comprising a body portion and a removable end cover therefor, of a controller having a series of stationary contacts secured within said body portion and a movable contact-connecting member mounted upon and sustained by the inner face of said cover, a brake device mounted upon the outer face of said cover, an operative connection between the movable member of said controller and said brake device, and controller actuating means.
9. An electric motor comprising a casing constructed with a body portion carrying a plurality of magnetic pole-pieces and a removable end cover for said casing having an inwardly extending tubular bearing boss, a motor-shaft journaled in said bearing boss, an armature mounted upon said shaft intermediate the pole-pieces, a plurality of fixed contacts mounted within the body of the casing, a series of field-coil sections each connected with one of said fixed contacts, a controller-arm journaled upon the tubular bearing boss of said end cover of the casing and provided with connected brushes adapted for establishing electrical connection between said fixed contacts, and means for operating said controller-arm.
10. An electric motor comprising a casing constructed with a body portion carrying a plurality of magnetic pole-pieces and a removable end cover for said casing, a motor-shaft, an armature mounted upon said shaft intermediate the pole-pieces, a plurality of fixed contacts mounted within the body of the casing, a series of field-coil sections each connected with one of said fixed contacts, a pivotally mounted con-

troller-arm provided with connected brushes adapted for establishing the electrical connection between said fixed contacts, a cam carried by said controller-arm and formed 5 with a segmental series of recesses, a spring-pressed stud in operative relation with said cam and adapted in conjunction therewith to produce an intermittent resistance to the movement of said controller-arm, and actuating means for said controller-arm.

11. An electric-motor comprising a plurality of magnetic pole-pieces and a rotary armature intermediate the same, a motor-casing composed of a body portion embracing 15 said pole-pieces and a cover closing one end of the same, a motor-shaft upon which the armature is mounted, a plurality of fixed contacts arranged concentrically with the motor-shaft, a series of field-coil sections 20 each connected with one of said fixed contacts, a controller-arm mounted concentrically with said shaft at the inner face of said cover and adapted for establishing electrical connection between said fixed contacts, a 25 hollow pulley fixed upon said shaft adjacent said cover with its rim in close proximity to the latter, a brake-lever mounted upon the outer face of said cover and carrying a shoe adapted for engagement with the inner 30 face of the pulley-rim, an operative connection extending through said cover between the brake-lever and controller-arm, and means exterior to said casing for actuating the controller-arm.

35 12. The combination with an electric mo-

tor comprising a frame constructed with a body portion and a removable end cover therefor and a motor-shaft, of a pulley mounted upon said shaft external to the end cover and having an annular flange extending toward the latter, a brake-lever fulcrumed upon said end cover intermediate the motor-shaft and the pulley-flange and extending in a direction opposite to that of rotation of said pulley and carrying a shoe 40 45 adapted for engagement with the inner face of said pulley-flange, and actuating means for said brake-lever.

13. In an electric-motor comprising a closed casing, a plurality of magnetic pole-pieces, a rotary armature intermediate the same, and a motor-shaft carrying said armature, a controller disposed within the motor-casing and comprising a plurality of 50 fixed contacts arranged concentrically with the motor-shaft and in close proximity to and within the magnetic influence of said pole-pieces, a movable controller member also arranged within the motor casing and adapted to engage and connect said contacts, 55 and means exterior to said casing for operating the controller member.

In testimony whereof, I have signed my name to this specification, in the presence of two subscribing witnesses.

HENRY L. ZABRISKIE.
